[57] CLAIM

The ornamental design for a connector for an electric supplier for electric car, as shown and described.

DESCRIPTION

FIG. 1 is a perspective view of a connector for electric supplier for electric car showing our new design;

FIG. 2 is a front elevational view thereof;

FIG. 3 is a rear elevational view thereof;

FIG. 4 is a top view thereof;

FIG. 5 is a bottom view thereof;

FIG. 6 is a left side view thereof;

FIG. 7 is a right side view thereof;

FIG. 8 is a perspective view of a second embodiment showing our new design;

FIG. 9 is a front elevational view thereof;

FIG. 10 is a rear elevational view thereof;

FIG. 11 is a top view thereof;

FIG. 12 is a bottom view thereof;

FIG. 13 is a left side view thereof; and,

FIG. 14 is a right side view thereof.

The dashed lines are environmental only and form no part of the claimed design.
